DESIGN FOR AN ASH TRAY

Arnold J. Schwisow, Hopkins, Minn.

Application May 9, 1946, Serial No. 129,500

Term of patent 7 years

(Cl. D85—2)

To all whom it may concern:

Be it known that I, Arnold J. Schwisow, a citizen of the United States, residing at Hopkins, in the county of Hennepin and State of Minnesota, have invented a new, original, and ornamental Design for an Ash Tray, of which the following is a specification, reference being had to the accompanying drawing, forming part thereof.

Figure 1 is a plan view of an ash tray, showing my new design;

Figure 2 is a side elevational view thereof;

Figure 3 is a top plan view of the removable central portion;

Figure 4 is a side elevational view of the removable central portion; and

Figure 5 is a top plan view of the outer tray portion.

I claim:

The ornamental design for an ash tray, as shown.

ARNOLD J. SCHWISOW.
